UNITED STATES PATENT OFFICE.

JAMES CHARLES, OF RICHMOND, INDIANA.

WATER-MOTOR.

1,296,622.

Specification of Letters Patent. Patented Mar. 11, 1919.

Application filed November 16, 1918. Serial No. 262,791.

To all whom it may concern:

Be it known that I, JAMES CHARLES, a citizen of the United States, residing in the city of Richmond, in the county of Wayne, State 5 of Indiana, have invented a new and useful Water-Motor, of which the following is a full, clear, and comprehensive specification, the same being such as will enable others to make and use the same with exactitude.

10 The object of my present invention, broadly stated, is to produce a water motor capable of developing a maximum amount of power with a minimum amount of water applied thereto, and to provide such a motor at a 15 comparatively low cost, and capable of being operated with a high degree of efficiency.

More specifically stated my object is to provide a water motor in which the wheel is 20 provided with vanes or blades of novel construction and arrangement, whereby the water under pressure when it impacts the vanes will be given a lateral zig zag motion, thereby exerting a compound wedge-like 25 movement to propel the wheel until the entire force of the water is spent, all of which power will be delivered to rotate the wheel.

Other subsidiary objects and advantages 30 of the invention will suggest themselves to the hydrodynamic engineer in the course of the following specification, and that which is new will be correlated in the claims.

The preferred means for carrying out the principles of this invention in a thoroughly efficient and mechanical manner is shown in 35 the accompanying drawings, in which—

Figure 1 is an edgewise elevation of my motor. Fig. 2 is a central vertical section, as taken on the line 2—2 of Fig. 1. Fig. 3 is an end elevation of the nozzle which delivers 40 water under pressure to the wheel. And Fig. 4 is a perspective view of one of the several vanes or paddles, which are all identical with each other.

Similar indices denote like parts throughout the several views.

In order that the principles and the construction of my invention may be better understood I will now take up a detailed description of one means for the embodiment 50 of the principles involved, but the invention is not to be limited to such details of arrangement.

In the drawings numeral 1 denotes the body or hub portion of the wheel, the same

being in the nature of a drum or cylinder 55 which is mounted on an axis or shaft 2, which is concentric thereof.

Projecting out from around each end of the hub 1, and rigid therewith, are the flanges 3 and 4 whereby a comparatively deep channel is formed entirely around the periphery of the hub or body 1 and between the space formed by the flanges 3 and 4. Numeral 5 denotes a frame which in this instance is secured to the base 6 and extends upward 65 therefrom and within which the said wheel is located. Said frame is provided with boxings or bearings 7 and 8 in which the shaft 2 is revolvably mounted. Secured on the outwardly extending projection of the shaft 2 70 is the pulley 9 from which power may be taken in the usual manner.

Spaced an equal distance apart and extending out from around the periphery of the hub 1 are a plurality of vanes or blades 10. 75 The said vanes are formed of comparatively thin suitable material, such for instance as sheet metal, and approximately one-half of the body of each is straight, while the remainder thereof is curved at a right-angle to 80 the other portion, whereby the extreme end part of the curved portion is at right-angles to the straight portion. A small right-angular flange *a* projects from the extreme end part of the straight portion in which there 85 are screw apertures *a'*, and also screw apertures *a''* are formed in the extreme end part of the curved portion. Also a flange *b* projects from the inner edge of each blade 10, and it has a plurality of screw apertures *b'* 90 formed therethrough.

The ends of each vane are adapted to be secured to the inner or opposing faces of the flanges 3 and 4 by means of screws inserted in the apertures *a'* and *a''*, and each vane is 95 adapted to be secured to the periphery of the body or hub portion 1 of the wheel by means of screws inserted in the apertures *b'*.

Said vanes or blades are located staggered or alternating right and left, that is to say: 100 The end *a* of the straight portion of each alternate vane is secured to the flange 3, while the other or end part of the curved portion is secured to the flange 4; and in like manner the end *a* of the other alternate vanes 105 are secured to the flange 4, while the other end thereof is secured to the flange 3. It is evident that this arrangement permits the end

of the curved portion of each vane to adjoin the end of the straight portion of the vane next thereto, thereby forming in reality a continuous vane entirely around the body or hub 1 and between the flanges 3 and 4.

Supported by the base 6 is a race for the wheel, the same being formed with its surface curved to correspond somewhat with the curvature of the wheel, and it is denoted as 10 the portion 11, with flanges 12 and 13 projecting up between and near to the respective flanges 3 and 4. Numeral 14 denotes a nozzle having an elongated narrow mouth 15. Said nozzle rests on the member 11, as 15 shown at the left in Fig. 2, with said mouth near to and directed toward the blades 10 at the lower portion of the wheel, as shown.

It is now evident that the water may be caused to enter through the nozzle 14 and 20 issue from the mouth 15 in a horizontal ribbon under high pressure, and it will be caused to impinge the vanes or blades 10 successively, first striking the flat portion and then passing wedge-like over the curved 25 portion, moving first to the right and then to the left, alternately, as the wheel revolves. The race-way, the flanges 12 and 13, and the flanges 3 and 4 of the wheel retaining the water in close contact with the 30 successive vanes, thereby causing the water to take a longer course before it is released and thereby causing the wheel to revolve at the maximum high rate of speed, or with a maximum of power, and causing every 35 particle of the accumulated force of the water to be utilized in driving the wheel with great power before the water is finally permitted to escape, as shown at the right in Fig. 2. In actual tests I have found that 40 when the water is permitted to pass straight through, as with ordinary vanes or buckets; and then with the same amount of water and pressure directed upon a wheel provided with vanes as set forth herein, that 45 the wheel would revolve with much greater speed under the latter than under the former conditions, thereby proving my theory to be correct.

Having now fully shown and described 50 my invention, what I claim and desire to secure by Letters Patent of the United States, is—

1. A water motor including a wheel having a cylindrical body, flanges extending 55 out from around the ends of the body, vanes radiating from the periphery of the body and connected with said flanges, one portion of each vane being straight and the other portion being curved at right-angles thereto, the curve of each vane being located opposite to the straight portion of the vane next thereto.

2. A water motor comprising a wheel having a cylindrical body, flanges projecting 60 out from around the ends of the body, vanes

radiating from the periphery of the body and connected with said flanges, one portion of each vane being parallel with the axis of the body and the other portion of each vane being curved with the end part of the 70 curved portion at right-angles to the axis of the body, the curved portion of each vane being on the opposite side, laterally, from that of the curved portion of each of the vanes next thereto.

3. A water motor having a wheel including a cylindrical body, flanges projecting out from around the ends of the body and concentric therewith, vanes radiating from the periphery of the body and contacting with said flanges, approximately one-half of each vane being parallel with the axis of the body and the other approximate one-half of each vane being curved with its end portion at right angles to the axis of the 80 body, said vanes being arranged staggered with relation to their positions on said body.

4. A water motor comprising a wheel having side flanges forming a channel around the periphery of the body of the wheel, a plurality of vanes located in said channel and equally spaced apart, each of said vanes being secured to the body of the wheel and to said flanges, the vanes being arranged to alternately extend straight from one 95 flange and then curve at right-angles to the other flange with the end of the straight portion of each vane meeting the end of the curved portion of the vane next thereto thereby forming a continuous vane extending 100 around the body of the wheel.

5. A water motor comprising a wheel having a cylindrical body, flanges radiating from the ends of the body, a plurality of vanes radiating from around the body with their ends in contact with both of said flanges, each alternate vane extending from one of said flanges in a direct line toward the other flange for approximately one-half its length and then curving at right-angles 110 to a point where it contacts with the other flange, the straight portion of each alternate vane being adjoining one of said flanges and the other alternate vanes having their straight portions adjoining the other flange, 115 means for revolvably mounting the wheel, and means for transmitting the power developed by the wheel.

6. A water motor comprising in combination with a base, a wheel having a cylindrical body, flanges radiating from the ends of the wheel body, a frame extending up from the base, a shaft carried by the frame and on which said wheel is mounted, a race corresponding with the curvature of the 120 wheel and located between said flanges, flanges extending up from the base and located between and adjoining the flanges of the wheel, curved vanes carried by the body the ends of said vanes being all con- 125 130

nected together entirely around the body of the wheel and approaching near the face of the race, a nozzle through which water may be directed against the vanes with said nozzle located between the said flanges of the base, and a pulley connected to said shaft, all substantially as shown and described.

In testimony whereof I have hereunto subscribed my name to this specification in the presence of two subscribing witnesses.

JAMES CHARLES.
